VENTILATOR FOR COLD STORAGE CHAMBERS

Pierre Pouliot, Jacksonville, Fla.

Application July 12, 1948, Serial No. 38,246

3 Claims. (Cl. 98—119)

1

This invention relates to new and useful improvements and structural refinements in ventilators, and the principal object of the invention is to assure satisfactory and automatic ventilation of cold storage chambers such as refrigerators, meat boxes, and the like.

Particularly, the invention concerns itself with cold storage rooms used by butchers, wherein the low temperature causes the formation of vapor condensation on the ceilings, with the result that the condensed moisture drops from the ceilings and is a source of considerable inconvenience and discomfort to persons who enter the cold storage rooms.

It is, therefore, an important feature of the instant invention to provide ventilating means for the upper strata of the cold storage rooms, whereby comparatively warm air in the strata is automatically discharged from the room and the possibility of vapor condensation is substantially minimized, if not completely eliminated.

Another feature of the invention resides in its automatic actuation, the ventilating operation being effected each time the door of the room is opened and closed.

An important advantage of the invention resides in its ability to retain cold air within the storage room, this being possible because the ventilator is not in operation unless the door of the room is opened and closed.

An additional advantage of the invention lies in its simplicity of construction and in its adaptability to installation in cold storage chambers of various sizes and types.

With the above more important objects and features in view and such other objects and features as may become apparent as this specification proceeds, the invention consists essentially of the arrangement and construction of parts as illustrated in the accompanying drawings, in which:

Figure 1 is a perspective view of the invention; Figure 2 is a vertical cross-sectional view thereof;

Figure 3 is a perspective view of one of the louvers used in the invention;

Figure 4 is a cross-sectional view, taken substantially in the plane of the line 4—4 in Figure 1;

Figure 5 is a fragmentary cross-sectional view, taken substantially in the plane of the line 5—5 in Figure 2; and

Figure 6 is a fragmentary cross-sectional diagram, showing the invention in association with a cold storage chamber.

2

Like characters of reference are employed to designate like parts in the specification and throughout the several views.

Referring now to the accompanying drawings in detail, the invention consists of a ventilator designated generally by the reference character 10, the same being primarily intended for use in association with cold storage chambers or rooms 12, such as are commonly employed by butchers, and the like.

These cold storage rooms or chambers usually assume the form of suitable enclosures provided with outwardly swingable doors 14 whereby access to the interior of the chambers may be had, as is indicated in Figure 6.

The ventilator 10 is provided preferably on the ceiling 16 of the chamber 12, to which end the ceiling is formed with a rectangular opening 18, in which the ventilator may be conveniently mounted.

The ventilator 10 itself, consists of a multi-sided, dome-shaped frame 20, including a perimeter base 22, which is secured to the inner surface of the ceiling 16 in register with the opening 18, while a set of upright supports 24, configurated substantially as shown, are secured to the base 22 and extend upwardly through the opening 18, as will be clearly apparent.

The supports 24 carry at their upper ends a top plate 26, the configuration of which will be hereinafter more fully described, and it is to be noted that the supports 24 are of an L-shaped cross-sectional configuration, being upwardly tapered and being provided at the longitudinal edges thereof with inturned flanges 28, as is best shown in Figures 4 and 5.

A set of louvers 30 is mounted at each side of the frame 20, these louvers in each set being superimposed and having longitudinal edge portions arcuated so as to provide tubular bearings 32 to accommodate shafts or rods 34, whereby the louvers are pivotally mounted between the supports 24 of the frame 20, as will be clearly apparent. The lower edge portions of the louvers 30 are inwardly angulated as at 36, the inwardly angulated portion of each louver in each set overlapping the tubular portion 32 of the next adjacent louver, substantially as shown in Figure 2. That is to say, this overlapping is present when the louvers are closed, but it is to be noted that the louvers are swingable outwardly as indicated by the arrows 38 in Figure 2, on which occasion the louvers in each set swing independently of one another.

It should be also explained that the louvers in

each set constitute what may be referred to as a shutter, the louvers being normally held in their closed position by the force of gravity.

However, when the invention is placed in use, closing of the door 14 will result in an increase in air pressure in the chamber 12, whereby the louvers 30 of the ventilator, responding to an air pressure greater than that of the atmosphere, will be caused to swing outwardly as indicated by the arrows 38, thus facilitating a discharge of comparatively warm air from the upper strata of the chamber 12. In this manner, condensation of vapor on the inner surface of the ceiling 16 will be substantially minimized, if not altogether prevented.

Needless to say, the louvers 30 will automatically return by gravity to their closed position, as soon as the air pressure within the chamber 12 becomes equalized with that of the atmosphere. It is to be particularly noted that inasmuch as the ventilator 10 is mounted upon the ceiling of the chamber, only the comparatively warm air in the upper strata of the chamber will be discharged, while the relatively cold air in the lower strata of the chamber will not have an opportunity to escape.

The aforementioned top plate 26 of the ventilator assumes the form of an inverted, multi-sided pyramidal deflector, having under surfaces which extend inwardly and downwardly from the uppermost louver in each set, as indicated at 40. (See Figure 2.) These inclined surfaces assure that the air passing outwardly through the ventilator is distributed equally through the various louvers, as will be clearly understood. Marginal edge portions of the plate 26 are angulated downwardly and inwardly to afford strips 26' of an L-shaped cross-section, the downturned portions of these strips overlying the outer faces of the posts 24 while the inturned portions of the strips extend inwardly to contact the uppermost louvers in the several sets.

It is believed that the advantages and use of the invention will be clearly apparent from the foregoing disclosure and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

1. A ventilator comprising a multi-sided base having a central air receiving aperture therein, posts attached to and rising from the corners of said base, each of said posts having a pair of inwardly extending vertically inclined flanges, each of said posts having one of its flanges in registry with one flange of an adjacent post, a set of vertically spaced horizontal pivot shafts associated with each pair of adjacent posts and terminally

attached to registering flanges of adjacent posts, said shafts of each set lying in an upwardly and inwardly inclined plane, a group of closure members associated with each pair of adjacent posts and including an upper closure member and a lower closure member, each of said closure members being elongated and having an inwardly rolled sleeve along one of its sides and an inwardly curved flanged portion along its other side, said sleeves receiving said shafts for vertical swinging movement of the closure members, the flanged portion of the upper closure member resting against the outer face of the lower closure member when said closure members are in their closed position, a cover plate supported upon the upper ends of said posts provided with downwardly and inwardly angulated marginal edge portions affording elongated strips having an L-shaped cross-section, the inwardly angulated portions of said strips extending inwardly of said ventilator between said flanges on adjacent posts and contacting the sleeve on the upper closure member of each group of closure members.

2. A ventilator comprising a base having a central air receiving aperture therein, a plurality of posts each having an L-shaped cross-section attached to said base and extending upwardly therefrom, each of said posts having one leg thereof disposed coplanar with the registering leg of the sidewise adjacent post, each of said posts having inwardly extending flanges on the vertically extending edges thereof, a set of horizontally disposed louvers vertically pivotally mounted on the registering flanges of adjacent posts for movement therebetween, a cover plate mounted on the upper ends of said posts and provided with downwardly and inwardly angulated marginal edge portions affording strips having an L-shaped cross-section, the inwardly angulated portions of said strips extending inwardly of said ventilator between the flanges on adjacent posts and contacting the uppermost louver of each of said sets of louvers.

3. The combination of claim 2 wherein the downwardly extending portions of said strips overlie the outer face of the registering legs of adjacent posts adjacent the upper ends of the posts.

PIERRE POULIOT.
